UNITED STATES PATENT OFFICE.

ARTHUR R. MONTFERRAND, OF BOSTON, MASSACHUSETTS, ASSIGNOR TO MEADER ENGINEERING AND MACHINE COMPANY, OF BOSTON, MASSACHUSETTS, A CORPORATION OF MASSACHUSETTS.

STRAP-TIPPING MACHINE.

1,281,052.

Specification of Letters Patent.

Patented Oct. 8, 1918.

Application filed May 28, 1918. Serial No. 237,039.

To all whom it may concern:

Be it known that I, ARTHUR R. MONTFERRAND, a citizen of the United States, residing at Boston, in the county of Suffolk and State 5 of Massachusetts, have invented new and useful Improvements in Strap-Tipping Machines, of which the following is a specification.

This invention has for its object to provide a machine for applying metal tips to flat straps or strips of textile fabric, the tip being, before its application to the strap, a metal cup of elliptical shape in cross section, and the strap end being compressed 10 edgewise to permit its insertion in the tip, the tip being compressed sidewise after the insertion of the strap-end, and thus provided with flat parallel sides between which the strap-end is securely clamped.

20 The invention is embodied in a strap-tipping machine comprising a press including a fixed bed and movable platen, said bed and platen being adapted to flatten an elliptical tip applied to a compressed strap-end, 25 a mold including a fixed member having a cavity formed to receive and bear on two sides and one edge of the strap-end, and a plunger movable in said cavity and adapted to bear on the opposite edge of the strap-end, 30 and means for imparting movement from the platen to the plunger, the mold being adapted to reduce the width of a strap-end inserted in said cavity, and thus permit the insertion of the strap-end in the tip before 35 the latter is flattened.

Of the accompanying drawings forming a part of this specification,—

Figure 1 is a front elevation of a strap-tipping machine embodying the invention.

40 Fig. 2 is an end view of the same, a portion being shown in section on line 2—2 of Fig. 1.

Fig. 3 is a side view of an end portion of a strap before its compression.

45 Fig. 4 is a view similar to Fig. 3 showing the strap-end compressed.

Fig. 5 is a view similar to Fig. 4, showing a compressed strap-end inserted in a partially formed tip, the latter being elliptical 50 in cross section.

Fig. 6 is a view similar to Fig. 5, showing the tip flattened and clamped to the strap-end.

Fig. 7 is a section on line 7—7 of Fig. 5.

Fig. 8 is a section on line 8—8 of Fig. 6. 55 The same reference characters indicate the same parts in all of the figures.

In the drawings, 12 represents a fixed press bed attached to a suitable frame 13 and having a flat top face. 14 represents a 60 platen which is movable toward and from the bed 12 by any suitable means. As here shown, the platen is reciprocated by means of an eccentric 15 attached to a driven shaft 16 and embraced by a strap 17 on a 65 link or rod 18 attached to the platen.

The throw of the platen is such that it approaches the bed sufficiently to change the form of a tip 19, containing a compressed 70 strap-end 20, from the elliptical form shown by Fig. 7, to the flattened form shown by Fig. 8.

Associated with the press is a mold 75 adapted to compress the strap-end and impart thereto the form shown by Fig. 4. Said mold comprises a fixed member 21 attached by bolts 22 to a fixed ear 23 projecting from one end of the bed 12, said member containing a mold cavity 25 formed to receive and bear on two sides and one edge of a flat 80 strap-end shown by Fig. 3, and a plunger 26 movable in said cavity and adapted to bear on the opposite edge of the strap-end and form a reduced portion 20 shown by Fig. 4. The member 21 is preferably a block having 85 a parallel sided slot formed in its outer end and provided with a flange 21^a attached by bolts 27, and forming one edge of a four sided mold cavity, the other three edges of which are formed by the sides and inner end 90 of the slot 25. The plunger 26 has a close sliding fit in the mold cavity, and is reciprocated therein preferably by the means next described.

29 represents a lever connected at one 95 end with the frame 13 by a fulcrum stud 30, and at the opposite end with the plunger 26 by a pivot pin 31. The lever 29 is interposed between the fixed ear 23 on the bed 12 and a movable ear 32 attached to the 100 platen 14 and overhanging the ear 23 and the lever. A spring 33 bearing at one end on the block or mold member 21, and at the opposite end on the lever 29, presses said lever upward and holds it in yielding contact with the platen arm 32. When the platen is reciprocated the lever 29 is oscillated conjointly by the arm 32 and the

spring 33, and the plunger 26 is reciprocated by the lever.

The operation is as follows:

The platen 14 and plunger 26 being raised, 5 the operator inserts a strap-end in the condition shown by Fig. 3, in the mold cavity 25. When the platen and plunger descend, the strap is compressed edgewise between the plunger and the flange 21^a the strap-end 10 being thus provided with a reduced portion 20 (Fig. 4). The operator then inserts the portion 20 in a partially formed tip 19 of elliptical cross section, as indicated by Fig. 7, and places the strap-end and tip on the 15 bed 12 while the platen is raised. When the platen descends, the tip 19 is compressed and provided with flattened sides, as shown by Fig. 8, the strap-end being firmly clamped between said sides. The change of form 20 imparted to the tip and strap-end by the press may be seen by comparing Fig. 5 with Fig. 6, and Fig. 7 with Fig. 8.

The platen ear 32 is preferably adjustable to vary the extent to which the plunger 26 is depressed, and thus adapt the machine 25 to straps and tips of different sizes. To this end, the ear 32 may be provided with an adjustable stop member 32^a, formed as a screw adjustably engaged with the ear 32, 30 and bearing at its lower end on the lever 29, the said screw being maintained at any desired adjustment by means of a nut 32^b.

To insure close contact between the inner 35 edge of the plunger and the wall of the slot which forms the inner end of the mold cavity 25, I provide a biasing spring 35 interposed between an upwardly projecting arm 26^a on the plunger 26 and an abutment 36 on the lever 29, said spring exerting 40 pressure in the direction of the arrow 37 (Fig. 2) on the arm 26^a, and holding the inner edge of the plunger in close contact with the inner wall of the mold cavity.

The ear 23, the portion of the member 21 45 bearing thereon, and the bolts 22 constitute an embodiment of means for securing the member 21 to the press bed 12 in a position offset from the acting surface of the bed. The lever 29, arm 32, and spring 33 constitute 50 an embodiment of means offset from the acting surface of the platen 14 for imparting movement from the platen to the plunger 26. The mold is therefore adapted to act on and reduce a strap-end located 55 outside the path of movement of the platen, and the press is adapted to compress a partially formed tip 19 applied to the reduced end of the strip and located on the press bed.

I claim:

60 1. A strap-tipping machine comprising a press including a fixed bed and a movable platen, a mold including a fixed member having a cavity formed to receive and bear on two sides and one edge of a flat strap-end, and a plunger movable in said cavity

and adapted to bear on the opposite edge of said strap-end, means for securing said fixed member to the press bed in a position offset from the acting surface of the bed, and means offset from the acting surface of the platen for imparting movement from the platen to the plunger, the mold being adapted to act on and reduce a strap-end located outside the path of movement of the platen, and the press being adapted to compress 75 a partially formed tip applied to the reduced end of the strip and located on the press bed.

2. A strap-tipping machine comprising a 80 press including a fixed bed and a movable platen, a mold including a fixed member attached to the platen and having a cavity formed to receive and bear on two sides and one edge of a flat strap-end, and a plunger movable in said cavity and adapted 85 to bear on the opposite edge of said strap-end, a lever fulcrumed at one end to a fixed support and pivoted at the opposite end to said platen, an arm carried by the platen and bearing on said lever, and a lever-raising 90 spring holding the lever in yielding contact with said arm, the lever being oscillated by the platen and spring, and the plunger reciprocated by the lever.

3. A strap-tipping machine comprising a 95 press including a fixed bed and a movable platen, a mold including a fixed member attached to the platen and having a cavity formed to receive and bear on two sides and one edge of a flat strap-end, and a plunger movable in said cavity and adapted to bear on the opposite edge of said strap-end, a lever fulcrumed at one end to a fixed support and pivoted at the opposite end to said platen, an arm carried by the platen and bearing on said lever, a lever-raising spring 100 holding the lever in yielding contact with said arm, the lever being oscillated by the platen and spring, and the plunger reciprocated by the lever, the plunger being provided with an upwardly projecting arm, and a biasing spring interposed between said arm and an abutment on the lever, whereby the inner edge of the plunger is pressed 105 against the inner edge of said cavity.

4. A strap-tipping machine comprising a 110 press including a platen having a fixed ear at one end, and a movable platen having an ear overhanging said fixed ear, a mold including a fixed member attached to said fixed ear and having a cavity formed to receive and bear on two sides and one edge of a flat strap-end inserted in said cavity, and a plunger movable in said cavity and adapted 115 to bear on the opposite edge of the strap-end, a lever interposed between said ears, fulcrumed at one end to a fixed support, and pivoted at the opposite end to said plunger, and a lever-raising spring seated at one end on said fixed ear, and at the opposite end on 120

125 said fixed ear, and at the opposite end on 130

said lever and holding the latter in yielding contact with said movable ear, the lever being oscillated by the platen and spring, and the plunger reciprocated by the lever.

5. A strap-tipping machine comprising a press including a platen having a fixed ear at one end, and a movable platen having an ear overhanging said fixed ear, a mold including a fixed member attached to said 10 fixed ear and having a cavity formed to receive and bear on two sides and one edge of a flat strap-end inserted in said cavity, and a plunger movable in said cavity and adapted to bear on the opposite edge of the 15 strap-end, a lever interposed between said

ears, fulcrumed at one end to a fixed support, and pivoted at the opposite end to said plunger, and a lever-raising spring seated at one end on said fixed ear, and at the opposite end on said lever and holding 20 the latter in yielding contact with said movable ear, the lever being oscillated by the platen and spring, and the plunger reciprocated by the lever, the said movable ear being provided with an adjustable stop member bearing on the lever. 25

In testimony whereof I have affixed my signature.

ARTHUR R. MONTFERRAND.
